UNITED STATES PATENT OFFICE.

EDWARD A. LEVICK, OF HALIFAX, PENNSYLVANIA.

CHAIR-SEAT.

No. 894,020.

Specification of Letters Patent.

Patented July 21, 1908.

Application filed March 6, 1908. Serial No. 419,546.

To all whom it may concern:

Be it known that I, EDWARD A. LEVICK, a citizen of the United States, residing at Halifax, in the county of Dauphin and State of Pennsylvania, have invented certain new and useful Improvements in Chair - Seats; and I do hereby declare the following to be a full, clear, and exact description of the invention, such as will enable others skilled in the art to which it appertains to make and use the same.

I have produced an improved upholstered chair-seat or back of novel construction and as an article of manufacture adapted to be fastened to the chair-frame, and in the claims appended hereto I will set out the precise construction wherein my improvement resides, in connection with the accompanying drawing, in which,—

20 Figure 1 shows in perspective an upholstered chair-seat, the cover and the base-plate being partly broken away at the front edge to show the inturned or folded edge of the base-plate as the means of fastening to the underside thereof a bracing border frame provided with integral spurs or prongs as the means of attaching the cover to said border frame and producing thereby a braced seat ready for being fastened to the chair frame.

30 Fig. 2 is a vertical section of the same showing the manner of securing the cover to the border frame and the seat to the underside of the chair-frame. Fig. 3 shows in perspective the underside of the base-plate and the

35 separate border plates having the integral cover attaching spurs and secured to the base-plate by inturned or folded edge thereof the fastened edges of the cover being partly broken away. Fig. 4 shows in perspective one of the border bracing strips and its integral cover attaching spurs and fastening tongues. Fig. 5 shows the underside of the 40 seat corner and the lapping ends of the strips, the base lap being broken.

45 The support or base 1, of the seat is of sheet metal conforming to the shape of the seat and having an underlap 2, around its edges of about a quarter of an inch wide. A metal strip 3, about an inch wide and formed 50 with a plurality of integral spurs or prongs 4, standing downward along the edge of the underlap, is set upon the base beneath its edge underlap and the latter being hammered down upon the strip secures it to the lap and 55 to the base so that the ends of two of these spurred strips being lapped at the ends as at

5, upon the other strip and clamped together upon the base, form a border frame for the base and brace and strengthen it so that it cannot sink in the middle under the weight 60 of the occupant of the chair. This border frame serves also by its spurs as the attaching means for the cover which, being lapped under the base-lap, has a row of slits by which it is engaged with the spurs and the 65 latter being then hammered down inward on the cover clamp it to the border frame.

Before the cover is secured a filling of yielding material 6 is properly placed and packed between the covering and the base. 70 The seat may be fastened at its underside to the chair-frame and for this purpose two or more of the strips may have one or more integral tongues 7, standing downward in position to be nailed to the inner edge of the 75 chair seat supporting frame. With these fastening tongues the border frame will then serve as the means of fastening the cover to the base and also the means of fastening the seat to the chair. The provision of the under 80 edge lap of the base, while forming a bracing rib, serves the more important purpose as a fastener for the border frame and these two bracing elements give the advantage of using cheap and thin sheet tin for the seat-base. 85 By making the border-frame of separate strips they can be set separately under the base underlap and all the strips then clamped together by the overlapped base edges.

The provision for fastening the seat to the frame beneath the seat, renders it convenient for removing the seat and opening the cover to renew the filling. It will be noted that each strip of the border frame, is clamped along its edge to the base by the 95 parallel underlapping part 2 of the base. Each end 5, of each side strip is lapped upon the corresponding ends of the connecting strips and under the edge lapping part 2 of the base, so that one edge and each end of each 100 strip is clamped firmly upon the base by its underlap, so that the border frame practically forms a supplemental bottom for the seat.

When the separate spurred strips are secured by the clamping function of the base 105 underlap to the underside of the base, they form, by the lapping of the ends of said strips, a connected border frame; and in assembling the strips to form said frame, it is only necessary to place them within the base-lap and hammer it down thus making the base the means of securing the border-frame,

and the latter the means of securing the cover.

I claim:

1. A chair-seat, comprising a base of sheet metal formed with an underlap around its edges, a border-frame formed of strips, each with integral spurs or prongs, and adapted to be set under said underlap and clamped thereto and to the base, said strips forming a border strengthening and bracing frame for the base, and a cover fastened to the spurs of the separate border-frame.
2. A chair-seat comprising a base of sheet metal formed with an underlap around its edges, a border frame formed of separate strips each with integral spurs and adapted to be set under said underlap and clamped thereto and to the base, said strips having integral tongues on their inner edges standing downward and adapted to be fastened to the chair frame beneath the seat, and a cover fastened to the spurs of the said separate border-frame.
3. A chair bottom consisting of a base of sheet metal formed with an underlap around its edges, a frame, forming a border for the base and secured thereto by said underlap, and having integral spurs along the edges of said underlap, means depending from said border frame and adapted to be fastened to the chair-frame beneath the bottom of the seat, and a cover fastened to the spurs of the separate border-frame.
4. A chair bottom comprising a base of

sheet metal formed with an underlap around its edges, a border-frame composed of separate strips of sheet metal each having integral spurs and each fastened to the base by said underlap, and a cover fastened to the spurs of the said separate strips.

5. A chair bottom consisting of a sheet metal base formed with an underlap around its edges a border-frame of strips of sheet metal, each strip formed with integral spurs, one end of each strip adapted to be set under said underlap, and the ends of one parallel pair of strips lapping upon the ends of the other pair, and the strips so arranged that they will be separately and together clamped upon the base by said underlap.

6. In a chair-seat, the combination of a metallic base having underlapped edges, with a separate border-frame having integral cover attaching spurs and clamped to the base around its edge portion by means of said underlaps, the said border-frame having also integral chair attaching tongues whereby the border frame provides the means of fastening the cover to the base and the base at its under side to the chair-frame.

In testimony whereof I have signed my name to this specification in the presence of two subscribing witnesses.

EDWARD A. LEVICK.
